[57] **CLAIM**

The ornamental design for the game board data packages, as shown and described.

DESCRIPTION

FIG. 1 is a top plan view of a game board data package, showing my new design;

FIG. 2 is a front elevational view thereof, the rear elevational view being a mirror image of the front view shown;

FIG. 3 is a front side view thereof, the left side view being a mirror image of the sides shown; and,

FIG. 4 is a bottom view thereof.

The broken lines showing indicia are for illustrative purposes only and form no part of the claimed design.
